UNITED STATES PATENT OFFICE.

JOHN LEND, OF CHICAGO, ILLINOIS.

VIBRATING, TENSION, AND OPERATING TABLE.

937,825.

Specification of Letters Patent. Patented Oct. 26, 1909.

Application filed April 9, 1908. Serial No. 426,155.

To all whom it may concern:

Be it known that I, JOHN LEND, a citizen of the United States, and a resident of Chicago, Cook county, Illinois, have invented 5 certain new and useful Improvements in Vibrating, Tension, and Operating Tables; and I do hereby declare that the following is a full, clear, and exact description of the same, reference being had to the accompanying drawings, and to the letters of reference marked thereon, which form a part of this specification.

In many of the ailments afflicting mankind, at least one of the causes may be found 15 in the undue pressure brought upon certain nerves and blood vessels and arteries due to malformations and to deformities in the cervical, dorsal or lumbar portions of the spinal column whereby the cartilaginous pad 20 between the vertebrae are reduced in thickness sufficiently to somewhat pinch or compress the nerves and blood vessels or arteries accompanying the same where they pass into or out of the spinal column. Frequently 25 also calcareous or limy deposits, particularly in some forms of rheumatism are formed between the vertebrae thus rendering the cartilaginous pads of almost a bony nature and in such cases destroying the flexibility 30 of the spinal column. In such cases, obviously, medicinal and surgical treatment can be of but little or no avail and while massage and mechanical extension attending to relieve the pressure and tending also to 35 gradually more or less break up the calcareous deposits and remove the same by exciting the vascular system in that region, to greater activity may afford relief. In such cases, it has been found that to apply tension 40 sometimes to the extent of several hundred pounds to the spinal column or those portions of the spinal column affected and at the same time exciting the nerves and vascular system to increase activity by rapid 45 vibration of the bench or to massage either with or without hot or cold applications and if desired, electrical applications, have proved effective where other means have failed. Of course, where similar troubles 50 have affected other joints, as for instance, the joints of the arm or leg, similar extension, vibration, massage with or without attendant hot or cold and electrical applications are effective to afford relief and to excite 55 and stimulate the nerves and vascular

system in that region to remove the cause of the trouble.

With this in view, it is the object of this invention to afford a tension table provided with mechanism whereby any joint or joints 60 of the patient may be subjected to powerful yet careful and graduated tension and at the same time subject the affected region to intense vibratory action.

It is also an object of the invention to so 65 construct the operating table as to permit massage to be applied to the afflicted area.

It is also an object of the invention to construct the operating table and the mechanism attached thereto so as to afford a comfortable and well padded support for the patient while undergoing operation and to permit any portion of the support to be removed from beneath the patient to permit the application of massage, hot or cold, 70 applications, electrical or other treatment.

It is also an object of the invention to afford in connection with an operating table of the class described mechanism whereby the cervical portion of the spinal column 80 may be subjected to tension to the extent desired, but may also be subjected to a rotational movement to restore to that portion of the spinal column its normal facility to motion.

It is finally an object of the invention to afford a construction in which such simplicity, strength and rigidity are assured as to protect the patient from undue strain due to any sudden failure of any part of the 90 mechanism and in which the actuating means for the mechanisms are provided and whereby the tension exerted upon the patient can be carefully graduated by the operator who manually actuates the tension devices. 95

The invention embraces many novel features and consists in the matters hereinafter described and more fully pointed out and defined in the appended claims.

In the drawings: Figure 1 is a side elevation of a device embodying my invention. Fig. 2 is a top plan view of the same. Fig. 3 is an enlarged section taken on line 3—3 of Fig. 2. Fig. 4 is an enlarged detail section showing the vibrating mechanism in 100 side elevation. Fig. 5 is an enlarged section taken on line 5—5 of Fig. 2. Fig. 6 is an enlarged section taken on line 6—6 of Fig. 2. Fig. 7 is an enlarged section on line 7—7 of Fig. 2. Fig. 8 is an enlarged fragment 110

5 tary section on line 8—8 of Fig. 2. Fig. 9 is an enlarged detail of the lock whereby the tension when applied is maintained. Fig. 10 is an enlarged fragmentary vertical section on line 10—10 of Fig. 2. Fig. 11 is 10 an enlarged end view of the jaws and vibrating shaft. Fig. 12 is an enlarged fragmentary top plan view illustrating the pivot bearing for the vibrating shaft.

15 As shown in the drawings: Said table comprises a strong frame of requisite length and width consisting of side rails A, end rails A'—A², and supported upon legs a, constructed of either wood or metal as preferred, but of such strength as to insure great rigidity and satisfactory support for the operating mechanism and the weight of the patient.

20 Rigidly secured on each of the side rails and projecting inwardly are brackets B—B', which may conveniently be constructed of cast metal rigidly bolted to the side rails and on the top of which, extending for the entire length of the table and rigidly secured to the end rails are lateral tracks b, 25 parallel with the side rails and but a short distance therefrom.

25 Rigidly secured on the extremities of the brackets B, and to the head rail A², at the head of the table are short track sections b', said tracks, as shown, in each instance consist of steel channel bars, the channel bars forming the track b, being bolted upon said brackets with the flanges thereof projecting upwardly and the channels forming the track rails b', being bolted to the ends of the channel as shown in Figs. 2, 8 and 10, with the flanges thereof directed inwardly. Journaled transversely the table intermediate the middle thereof and the end rail A', are 30 rotative shafts C—C', provided at one side the table with intermeshing gears c—c', rigidly secured on the respective shafts whereby said shafts of necessity rotate oppositely and secured on the outer end of the shaft C, 35 is a hand wheel c², for rotating the shafts. Said shafts are journaled close beneath the track rails b, and rigidly secured on the middle of the shaft C' is a gear or pinion c³, 40 and secured on the shaft C, near the inner side of each of the track rails b, are pinions c⁴.

45 Extending longitudinally and centrally of the table from near the middle thereof to the foot rail A' is a rack bar d, with which the pinion c³, on the shaft C' meshes, as shown in Fig. 5, and rigidly secured on the rear end of said rack bar is a transverse bar D, which at its ends is provided with 50 downwardly directed heads d', which fit in and slide in the channels forming said lateral track b. Rigidly bolted on said rail and centrally thereof is the lower member d² of the leg clamps. Said lower member, 55 as shown, consists of a raised saddle piece

of requisite length directed transversely the machine and having near each end thereof a semi-circular seat d³. Hinged at one end in any suitable manner of the saddle piece d², is the complementary upper clamping member d⁴. Said upper clamping member is conveniently of the same length as the saddle member and is provided on the under side with semi-circular seats d⁵, corresponding and registering with the seats of the saddle member, as shown in Fig. 5, and as shown, seats in both members are carefully padded or upholstered to prevent injury of the members, as for instance the ankles of the patient when clamped therein. The extremity of the lower clamping or saddle member opposite from the hinge is provided with a longitudinal upwardly and outwardly opening slot, in which is pivotally engaged in a bolt d⁶ adapted to extend upwardly through a corresponding slot in the end of the upper clamping member and threaded for engagement by a corresponding nut d⁷, whereby the clamp may be rigidly secured in closed position.

60 Supported on the track rails b, near the middle of the table is a rigid frame E, as shown constructed of angle bars rigidly bolted together with the webs thereof extending inwardly and the flanges upwardly of the outer side and affording a strong rectangular frame on which the patient is to be supported. Said frame is provided on its under side at convenient points with rollers or track wheels e, which run in said channel tracks b, and if preferred and as shown, said rollers may be provided with rubber tires. Extending transversely said frame and intermediate the middle and the end thereof and bolted thereto is a channel bar e', the web of which is directed toward the foot of the table and the flange of which is directed upwardly and between the foot end of said frame and said angle bar e', and resting on the webs of the lateral frame members are transverse slots E', on the tops of which are carefully upholstered pads e², on which the patient lies. Rigidly bolted on one of said frame members near the middle thereof is a knuckle e³, having a vertical cylindric aperture therethrough, in which is rotatably engaged a cylindric pin e⁴, adapted to be rigidly held from rotation by means of a set screw e⁵. The head e⁶ of said pin projects above the knuckle and is transversely slotted and apertured to receive therein the ends e⁷, of a bar e⁸, which is hinged thereto by means of a pivot pin e⁹, inserted through the head of said pin and the aperture in said bar. Said bar is curved in semi-circular form and extends above and across said frame and at its opposite end is adapted to receive therethrough a threaded end of an eye bolt e¹⁰ pivotally engaged on the opposite frame member, and

which is provided with a nut e^{11} , which rigidly locks said bar in position, and as shown, extending through suitable loops e^{12} , secured in the under side of the bar and centrally 5 thereof is the strap e^{13} , adapted to be secured about the body of the patient, if desired, to partly support his weight and in any event, to confine the patient to the table. Said frame is provided longitudinally on the opposite sides thereof and in close relation 10 with the side frame members with rack bars e^{14} , with which the pinions e^4 on the shaft C, mesh and whereby when the hand wheel e^2 is rotated, said frame and said foot clamp 15 D, are moved oppositely either toward or from each other.

Rigidly bolted to the end frame member E², at the head of the machine on each side thereof and near the end thereof are the 20 brackets F, directed toward the head of the table and extending upwardly from which and rigidly secured thereto are bolts f, on which are secured washers f', the under sides of which are riveted or provided with teeth 25 having abrupt faces directed toward the foot of the table and threaded on said bolts to bear on said washers are nuts f². Extending longitudinally of the table and resting on the head frame member E², and 30 transverse bar e', are bars F', one on each side of said movable frame and which are longitudinally slotted and from the front end to a considerable portion of their length to receive said bolts f therethrough and 35 which are provided with ratchet teeth on their upper side directed toward the head of the table and complementary with the ratchet teeth on said washer f', and whereby said washers may be adjusted longitudinally of 40 the table and rigidly engaged on the movable frame when adjusted.

At the rear end of each bar and at a position to engage in the axilla of the patient are upwardly directed brackets F², the upward sides f⁴ of which are upholstered to 45 fit beneath the arms and the rear portions of which afford broad and comparatively thin curved webs f⁵, which are curved upwardly and inwardly to engage about the patient's chest or trunk. Extending downwardly from each bar and pivotally engaged thereon is a stud f⁶, each provided with 50 an aperture extending transversely therethrough, one of which is provided with a left thread and the other with a right thread to engage opposite right and left threaded ends of shaft f⁷, whereby the rear ends of 55 said bars F' may be adjusted inwardly or outwardly to bring the shoulder pad f⁸ into 60 proper position for the patient. A hand wheel f⁹ is provided on one end of said shaft for actuating the same.

Journaled longitudinally of the table in 65 bearings G—G' secured centrally on the bar e' and frame bar E², is a shaft g, adapted

to be rotated to some extent by hand wheels g', and feathered on said shaft is a headrest G², shaped in its upper side to fit the head and the back of the neck of the patient and padded with upholstery material g³. 70 Rigidly secured on one side of the headrest is an upwardly directed strap g⁴, adapted to be brought beneath the chin of the patient and secured on the opposite side of the headrest in any suitable manner, thereby confining the head of the patient to the headrest and enabling tension to be applied to the neck if desired, while permitting the head to be rotated by means of the hand wheel. 75

Slidably secured in the track formed by the channel rails b', is the motor frame, which also carries the vibrating mechanism. Said motor frame may be constructed of wood or any suitable material and comprises transverse bars H—H'—H² rigidly connected in any suitable manner in parallel relation and to secure strength, and which extend into channels of said track rails b', to slide therein. Connecting and rigidly secured to the rails H'—H² are longitudinal bars h⁸, one on each side of the center and on which is supported for adjustment longitudinally of said bars a pivot post h⁴. As shown, said post is provided with a broad base adapted to slide in suitable rabbets in the top and inner sides of said bars and is adapted to be rigidly clamped by means of a stud screw h⁵. The upper end of said post is slotted longitudinally the frame and pivotally engaged therein is a sleeve h⁶, 100 through which extends the vibrating shaft h⁷, and as shown, a set screw h⁸ extends through said sleeve to engage the shaft to rigidly screw the same in the sleeve after the adjustment of the post on the frame, and whereby said shaft h⁷ may be adjusted on said post to vary the length of the portions extending beyond the pivot bearing thus varying the amplitude of vibration to be effected by the shaft. Said shaft is pivotally engaged at the center of said head end frame member E² and at the forward end of the shaft and rigidly secured thereon is a head h⁹, provided with a horizontal slot 105 therein on the upper and lower sides of which are journaled rollers h¹⁰. Mounted on said frame and rigidly secured to the frame members H—H' is a motor H³, shown as an electrical motor of any suitable kind, and the shaft of which extends upwardly and is journaled in its upper end on a bracket h¹¹, rigidly secured to the frame. Rigidly secured on the motor shaft in position for its rim to project between the rollers h¹⁰ secured in the head h⁹ on the 110 vibrating shaft, is a cam wheel h¹², of uniform thickness and diameter, but the sides or faces of which are waved uniformly to provide any desired number of vertical oscillations for the vibrator shaft with each rotation. 115

tion of the motor shaft, so that as said cam wheel revolves the head end of the extension frame on which the patient lies is vibrated very rapidly up and down, the rate of vibration depending upon the motor speed and the number of inclines or cam portions on said cam wheel, the amplitude of the vibration, of course, depending upon the adjustment of the pivot post toward or from the extension frame.

The operation is as follows: The patient having been placed upon the padded top of the extension frame, the ankle may be secured in the ankle clamp and the strap ¹³ 15 on the arch bar ⁸ is secured about the body to confine him to the machine. The shoulder brackets ³ are then fitted into the axilla for this purpose the stud ends ² being loosened to permit the bar F' to be adjusted to 20 suit the height of the patient and to bring the shoulder brackets to the right position, and then set up to rigidly secure the same against the tension to be exerted. The ends of the bars are swung inwardly or outwardly 25 to adjust the shoulder pads and brackets integral therewith close against the shoulders and trunk with the curved portions closed against the chest. Should it not be desired to exert tension upon the neck of the patient, 30 the head may rest in the head-rest though it is desirable to secure the head in place by means of the chin strap ⁴. Vibration is now started up by means of the motor and as the vibration continues, the hand wheel ³⁵ ² is rotated to gradually force the ankle clamps and tension frame oppositely until the desired tension is attained. When this is accomplished the tension may be maintained by means of the detent shown in Fig. 40 9, which comprises a toothed wheel K, secured on either of the shafts C or C', and a spring pawl ⁶ secured on the side rail of the table in position to engage the teeth of said wheel. The operation, of course, may 45 be continued as long as the same may be deemed desirable and during the period of vibratory tension treatment should be desired, massage, either mechanical or otherwise may be applied to any portion of the 50 back or neck of the patient by removing the slat E' under the portion it is desired to treat, from the table, and thus affording access from below to the surface to be so treated or affected. In the same manner, of 55 course, should it be desired, hot or cold applications may be made or electrical treatment applied, the removable slats permitting ready access to any portion of the spinal region. In applying neck tension the shoulder pads may be adjusted merely to serve as a 60 partial support and to steady the patient somewhat, or need not be used at all, if preferred. Tension when applied, is thus exerted by means of the head connection and 65 during the period of tension and vibration

the head may be rotated to a greater or less extent, vibratory action enabling the rotation to be effected with less pain than would be the case otherwise. Of course, in applying tension to the arms mainly or to the legs 70 mainly, the head is permitted merely to rest in the headrest and any suitable extensions from the foot clamp may be used to engage the wrists. If the arms are to be subjected to tension, the shoulder pads are, of course, 75 adjusted into place and the tension applied as before described, with the exception that the ankle clamp operates on the wrists instead of on the ankles.

From the construction described a great 80 variety of applications are possible, and, of course, there can be no jar to the patient during the vibratory action owing to the wheels or rollers supporting the extension frame being rubber tired. The machine may, 85 of course, be used as an operating table for those desiring to apply massage manually or mechanically without reference to the mechanical extension and vibrating apparatus and affords, owing to its construction 90 an excellent operating table for osteopathic treatment.

I have shown but one of many possible constructions embodying my invention. I therefore do not purpose limiting this application for patent otherwise than necessitated by the prior art, as very many details of construction and operation may be varied without departing from the principles of this invention.

I claim as my invention:

1. A machine for applying tension to the human body, embracing oppositely movable clamping members to engage the limbs and parts of the body, an extension frame for supporting the patient embracing a padded sectionally removable top, a padded head rest conforming to the head and means for turning the head rest transversely of the machine.

2. A machine for applying tension to the human body, embracing oppositely movable clamping members to engage the limbs and head, an extension frame for supporting the patient embracing a padded sectionally removable top, means for vibrating the frame vertically, clamping members for the chest and means for adjusting the same longitudinally and transversely of the removable top.

3. A machine for applying tension to the human body, embracing clamping members to engage the limbs and parts of the body and head, racks engaged thereto, pinions actuating said racks oppositely, an extension frame for supporting the patient embracing a padded sectionally removable top, means for oscillating the head clamp and means for adjusting the body clamps longitudinally and transversely of the extension frame.

4. A machine for applying tension to the human body, embracing oppositely movable clamping members to engage the limbs and the head, an extension frame for supporting the patient embracing a padded sectionally removable top, adjustable means for vibrating said frame, and combined clamping members, one part of each member padded to fit the axilla, and the other part of each member curved to engage over the chest.

5. A machine for applying tension to the human body, embracing oppositely movable clamping members to engage the limbs and parts of the body and the head, an extension frame for supporting the patient embracing a padded sectionally removable top, means for adjusting the clamps to the height of the patient, a motor carried by the machine, means operated thereby for vibrating the extension frame and means for applying a torsional movement to parts of the patient simultaneously with the vibration.

6. A machine for applying tension to the human body, embracing oppositely movable clamping members to engage the limbs and parts of the body and the head, an extension frame for supporting the patient embracing a paddle sectionally removable top, means adjusting the machine to the patient and vibrating mechanism for actuating the frame.

7. In a machine of the class described, means for engaging the limbs, a head clamp for applying tension to the cervical portion of the spine and means for rotating the head clamp while under tension.

8. In a machine of the class described, supporting means for the patient, means for clamping the limbs, an adjustable head clamp for applying tension to the cervical portion of the spine, means for rotating the head clamp while under tension and a vertically acting regulable vibrator for actuating the supporting means.

45 9. In a machine of the class described, means for clamping the feet, a vibrating head clamp for applying tension to the cervical portion of the spine and means for rotating the head clamp while under vibration and tension.

50 10. In a machine of the class described, padded clamps for engaging the limbs, a padded head clamp for applying tension and vibration to the cervical portion of the spine and means for partly rotating the head clamp while vibrating under tension.

11. In a machine of the class described, feet clamps, a vertically vibrating head clamp for applying tension to the cervical portion of the spine, means applying tension thereto and means for rotating the head clamp while under pressure.

60 12. In a machine of the class described, an ankle clamp, an extension frame, a head clamp affording part of the extension frame,

a rack secured to the ankle clamp and extension frame, pinions engaging the same to actuate the same oppositely and a detent for engaging said parts in adjusted position when under tension.

70

13. In a machine of the class described, a two part padded ankle clamp, an extension frame, a head clamp affording part of the extension frame, racks secured to the ankle clamp and extension frame, pinions engaging the same to actuate them oppositely, means for engaging said parts in adjusted position when under tension and a vibrator for actuating said mechanism vertically.

14. In a machine of the class described, means for applying vibratory treatment embracing a support for the patient, a vibrating bar pivoted thereon, a pivot post for said bar adjustable in the length thereof to vary the amplitude of vibration of the ends, a motor connected to vibrate or oscillate said bar and adjustable clamps for securing the body to the support.

15. In a device of the class described, an extension table, padded ankle clamps, mechanism for moving the same and table oppositely, chest clamps, shoulder clamps, means for adjusting said chest and shoulder clamps simultaneously oppositely, a rotatable head rest and mechanism adapted to vibrate the head rest, table, chest clamps and shoulder clamps.

16. In a machine of the class described, a vibratable frame for supporting the patient, means for vibrating the same and means for applying tension to the body and limbs of the patient while the frame is vibrating.

17. In a machine of the class described, a vibratable frame for supporting the patient, and adjustable clamps for engaging the chest or trunk of the patient.

18. In a machine of the class described, a vibratable frame for supporting the patient, adjustable clamps for engaging the chest or trunk of the patient and curved over the chest and a padded rest for receiving the head.

19. A vibrating, tension and operating machine embracing a supporting frame, and chest clamps adjustable longitudinally and transversely of the machine.

20. In a machine of the class described, a supporting frame, chest or trunk clamps and means for simultaneously adjusting the chest or trunk clamps oppositely.

120

21. In a machine of the class described, a supporting frame, chest or trunk clamps, means for simultaneously adjusting the chest or trunk clamps oppositely and means for independently adjusting the chest clamps to accommodate patients of different lengths.

125

22. In a machine of the class described, means for supporting the patient and means for rotating the head of the patient.

23. In a machine of the class described, a

130

- supporting table, a padded head rest, means for rigidly securing the head thereon and means for rotating the head rest to twist the neck of the patient.
- 5 24. In a machine of the class described, a supporting table and mechanisms for applying a tensile and a torsional tension to different parts of the body.
25. In a machine of the class described, a supporting table, means for longitudinally stretching the trunk, limbs and cervical portions of the body and means for applying a torsional tension upon the proper parts of the body.
- 10 26. In a machine of the class described, a supporting table, means for vibrating the same, and means for applying a torsional motion to the desired part of the body while the table is being vibrated.
- 15 27. In a machine of the class described, a supporting table, means for vibrating the same, means for applying a torsional motion to the desired part of the body while the table is being vibrated, and means for applying longitudinal tension to the body while the table is vibrating.
- 20 28. In a machine of the class described, a supporting table, a shaft, and a padded head rest on said shaft adapted to be rotated by the shaft.
- 25 29. In a device of the class described, a supporting table, padded ankle clamps, means for adjusting the ankle clamps and table oppositely and means for locking the adjusting means for any adjustment of the ankle clamps and table.
- 30 30. In a device of the class described, tracks, a supporting frame, wheels thereon supporting the frame on the tracks, independently removable padded sections supported by the frame, and means for vibrating the frame on the tracks.
- 35 31. In a device of the class described, tracks, a supporting frame, wheels thereon supporting the frame on the tracks, independently removable padded sections supported by the frame, tracks at one end of the aforesaid tracks, a vibratable frame supported on said tracks, a motor on said frame and operative connections between the motor and supporting frame.
- 40 32. In a device of the class described, a supporting frame, a motor frame, a motor thereon, vibrating connection between the supporting frame and motor frame and a removable padded top for the supporting frame.
- 45 33. In a device of the class described, a supporting frame, a motor frame, a motor thereon, vibrating connections between the supporting frame and motor frame, a removable padded top for the supporting frame, and mechanism secured to the supporting frame for confining the body and head thereto.
- 50 34. In a device of the class described, a supporting frame, padded removable sections secured thereto, and a bar pivotally secured to the frame at one end and curved over the frame for securing the body upon the padded sections and means for adjusting the bar for different sized bodies.
- 55 35. In a device of the class described, a supporting frame, padded removable sections secured thereto and a bar pivotally secured to the frame at one end and curved over the frame for securing the body upon the padded sections, means for adjusting the bar for different sized bodies and straps secured to the bar adapted to fasten around the body.
- 60 36. In a device of the class described, a supporting table, a bar curved to conform to the body adjustably secured at each end to the table, a head rest, feet clamps and means for adjusting the head rest and feet clamps.
- 65 37. In a device of the class described, a supporting table, padded clamps secured thereto to engage in the axilla and clamps extending from the pads curved to conform to the chest.
- 70 38. In a device of the class described, a supporting table, padded clamps secured thereto to engage in the axilla, clamps extending from the pads curved to conform to the chest, a padded head rest shaped to conform to the head, padded feet clamps and a body clamp.
- 75 39. In a device of the class described, a supporting table, padded clamps secured thereto to engage in the axilla, clamps extending from the pads curved to conform to the chest, a padded head rest shaped to conform to the head, padded feet clamps, a body clamp, a motor and means actuated thereby for vibrating the supporting table.
- 80 In testimony whereof I have hereunto subscribed my name in the presence of two subscribing witnesses.
